DOOR CONSTRUCTION

William E. Hergenrather, Dayton, Ohio

Application April 8, 1941, Serial No. 387,395

1 Claim. (Cl. 20—16)

This invention relates to so called over-head door constructions suitable for use in garages and other places where such types of doors can be used.

There are several types of over-head doors now on the market and some of them are rather hard to operate at times and many of them have complicated fixtures attached thereto to operate said doors. Also many of such doors are made in several hinged sections, varying from two to five. All this makes for expensive manufacture and is conducive to hard action at times. Moreover, in such doors there are many parts which may cause the doors to get out of proper working order comparatively easy.

Therefore, it is an object of my invention to produce an over-head door which is very easy to operate and inexpensive to manufacture.

Another object is to provide a novel door construction which will not warp or get out of alignment, which often happens due to stresses and strains to which many of the doors now on the market are subjected, when being opened and closed.

A further object of my invention is to provide a novel construction of mounting the door and arranged so as to eliminate any excessive friction during the movements of the door from closed to open position and vice-versa.

A still further object is to provide a novel counter-balance arrangement for the door which arrangement gives the maximum factor of safety.

Another object of my invention is to provide a novel over-head door construction, whereby there is no direct pull on the door when opening or closing the same.

With these and other incidental objects in view, my invention includes certain novel features of construction and combinations of elements, the essential parts of which are set forth in appended claims, and a preferred form or embodiment of which is hereinafter described with reference to the drawings which accompany and form part of this specification.

Of said drawings:

Fig. 1 is an elevation, partly in section showing in a very much reduced scale, my novel door construction, with the door in closed position.

Fig. 2 is an enlarged section on line 2—2 of Fig. 1, looking in the direction of the arrows.

Fig. 3 is a still further enlarged view showing a portion of one of the mounting brackets and its hub bearing.

Fig. 4 is a section on line 4—4 of Fig. 3, looking in the direction of the arrows.

Fig. 5 is a plan view of the cable support and pick-up arm.

Fig. 6 is a rear view of the same.

Fig. 7 is a side elevation of the same.

Fig. 8 is a section on line 8—8 of Fig. 1, looking in the direction of the arrows, and also shows the pulleys and counterweights in plan views.

Fig. 9 is a fragmentary view showing how a part of the weather strip is on the door and a part of said weather strip is on the door side jam.

Fig. 10 is a skeletonized view of the door and its mounting, and shows the door in its full open position, in full lines, and in the position where the pick-up arm picks up the cable to check any undue momentum as the door is being closed, and to balance the door from this point until it is fully closed.

Fig. 11 shows how my novel door construction can be operated by power means to open the door when it is closed, and act as a brake, and balance the door when the power means is reversed to close the door after it has been opened.

General description

25 Described in general terms my novel door construction is pivoted near each side thereof to swing over-head, by means of brackets attached to the door. Each bracket is provided with a bearing hub mounted on bolts in posts arranged 30 in the garage. Each bracket has secured thereto a cable pick-up arm to support the cable from the time the door is closed until it is quite near the dead center, at which time the arm leaves the cable and the door continues on past the dead center due to the momentum it has gained during its upward thrust while opening. After leaving the pick-up arm the cable pull is directly on the bracket, and not on the door, and therefore the door will not warp or become out of alignment due to stresses and strains usually attending the movements of door of this type. As the door is started on its downward movement in the act of closing, as soon as it gets a very short distance past the dead center, the pick-up arm 40 picks up the cable and acts as a snubber to prevent too much jar when the door is forced downwardly at too rapid a speed. The counter weights being fastened to the two cables act as a full counterbalancer and the door can be stopped in 45 any position after the cable pick-up arm has contacted the cable, due to the particular location in which the pick-up arm is placed relatively to the door mounting.

While I have shown and described a garage door, I do not wish to limit my invention to such

specific doors, as it is susceptible of embodiment in other doors for other purposes without departing from the spirit of my invention.

Detailed description

Referring to Figs. 1, 8 and 10 I have shown a garage door 20, and the usual right side door jam 21, left side door jam 22, and top door jam 23. On top of the jam 23 rest two stringers 24 and a plate 25 to support the front ends of roof rafters 26, supporting a comparatively flat roof 27. The floor is indicated at 28 and the usual apron at 29. Two posts 30 and 31 are secured in the floor 28 and are fastened to the rafters 26.

There is secured to the door 20 near the top and sides thereof, brackets 35 and 36. Both the left hand bracket 35 and the right hand bracket 36 are shown in Fig. 8; the right hand bracket 36 is also shown in Fig. 1; and a portion of said bracket 36 is shown in Figs. 3 and 4. These brackets are preferably made of angle irons or bars for strength. The right hand bracket is comprised of a vertical bar 40 secured to the door 20. Securely fastened to the vertical bar 40, by welding or any other suitable means, is a horizontal bar 41, and two other bars 42 and 43. The bars 41, 42 and 43 are in alignment as shown in Fig. 4, and they are also welded together along the joints 44 and 45.

The three bars 41, 42 and 43 are secured to a bearing hub 50, by welding or any other suitable means of fastening may be used.

The left hand bracket 35 is comprised of a vertical bar 51 (Fig. 8), a horizontal bar (not shown) but like the bar 41 of the bracket 36; and two bars 52, only one of which is shown. The last mentioned horizontal bar and the two bars 52 are welded together like the bars 41, 42 and 43, and are also welded to a bearing hub 55.

The bearing hubs 50 and 55 are mounted on bolts 56 (Figs. 3, 4 and 8) said bolts having shoulders 60 abutting washers 57 and are held in position by nuts 58 drawn up against washers 59. The shoulders 60 are slightly longer than the bearing hubs 50 and 55 so that the brackets 35 and 36 can swing freely thereon notwithstanding that the nuts 58 are drawn up very tightly against the washers 59, the head of the bolts 56 acting as lateral spacers for the brackets and through said brackets acting as aligning means for the door 20. The head of the bolt 56 holds the brackets 35 and 36 and the door 20 not only when the door 20 is closed but also during all of the time that said door is being moved from an open to a closed position and from a closed to an open position.

There are two cables 61 and 62 fastened to the brackets 35 and 36 at point marked 63, only one of such points being shown, and that one being in Fig. 1, where the cable 62 is fastened to the bracket 36. However the other cable 61 (Fig. 8) is fastened to the cable 35 at the same relative point.

The cables run upwardly over pick-up arms 66 and 67 (Figs. 1 and 8). The pick-up arm 66 is also shown in detail in Figs. 5, 6 and 7. This arm 66 has a base 70 by means of which it rests on and is secured to the bar 42 of the bracket 36 preferably by welding. A vertical section 71 of the arm 66 rises above the door 20 and has a channel 72 formed thereon to receive the cable 62. This arm 66 is also preferably made of angle-iron.

From the channel 72 the cable 62 passes over a pulley 75 carried by a hanger 76. The cable 62 is

secured to a counter weight 77 to assist in balancing the door 20 while being moved and assists in holding the door 20 open when the latter is wide open. The hanger 76 is supported by one of the rafters 26.

The pick-up arm 67 has a base 80, a vertical section (not shown) and a channel 82 to receive the cable 61. The base 80 rests on and is secured to the bar 52 of the bracket 35, preferably by welding. From the channel 82 the cable 61 passes over a pulley 85 carried by a hanger (not shown, but like the hanger 76), and is secured to a counterweight 87 which also assists in balancing the door 20 and assists in holding the door in its wide open position.

For further reference in describing the action of my novel door construction a vertical center line of the hubs 50 and 55 is designated as 90 and the horizontal center line of said hubs is designated 91. The vertical line 90 will be known as the "dead" center line.

When the door 20 is to be opened, the bottom part thereof is moved to the right (Fig. 1) whereupon the entire door 20 and brackets fastened thereto, pivots on the bolts 56 by means of the bearing hubs 50 and 55.

When the door 20 reaches the position shown in dot-and-dash lines (20) of (Fig. 10) the pick-up arm channels 72 and 82 leave the cable 62, which then is in the dot-and-dash position of Fig. 10. At this time all of the pull of the cables 61 and 62 is directly from the points 63 where said cables 61 and 62 are secured to the brackets 35 and 36. Prior to this time all of the pull of the cables 61 and 62 has been over the channels 72 and 82 of the pick-up arms 66 and 67. There is no direct pull on the door 20 proper, and therefore there is no stress or strain put on the door 20, thus eliminating all danger of warping the door and/or pulling it out of its proper alignment relative to the door jams 21, 22 and 23, and also the floor 28 and apron 29.

Usually during the normal operation of opening the door 20 the operator gives the door a shove or push and by the time the door reaches the dot-and-dash position of Fig. 10 it has gained sufficient momentum to carry it to the full open position shown by full lines in Fig. 10. In moving to this full line, or fully opened position the horizontal center line 91 passes the "dead" center line 90, and consequently the door 20 is held in this position by the counterweights 77 and 87. Due to the fact that the horizontal line 91 is past the "dead" center line 90 the door 20 cannot come down of its own weight even though the "bulk" of the weight of the door is normally below the horizontal line 91.

When the door 20 is closed, that is moved from its fully opened position to its closed position, it is first moved from the full line position of Fig. 10 to the dot-and-dash position of Fig. 10, at which point the channels 72 and 82 of the pick-up arms 66 and 67, respectively, pick up the cables 62 and 61, thus checking any undue momentum and balance the door 20, under the influence of the counterweights 77 and 87, from this point until the door 20 is fully closed. Movement of the door 20 can be stopped at any point in its travel and it will stay in such position until again moved by the operator.

From the above description it can be clearly seen that there is no direct pull on the door proper by the cables 61 and 62 during the closing of the door as well as during the opening of the door as previously stated. All of the

thrusts during all actions of the door 20 are taken on the bearing hubs 50 and 55 against the bolts 56.

To assist the operator in closing the door 20 there is attached to the inside face of the door a pull chain 93. When the door 20 is in the opened position of Fig. 10, the pull chain 93 will hang down at right angles, or substantially so, to the face of the door in easy reach of the operator, so that all he need to do is reach up and give a slight pull on the chain 93 to pull the door past the "dead" center line 90 after which the pull on the door can be lessened, whereby said door can be closed very easily.

As previously mentioned the door 20 can be opened and closed by a power means if desirable, and in Fig. 11 there is illustrated one form of a power means to accomplish this purpose.

Mounted in bearing brackets 100, which may be fastened to any of the usual cross beams of a garage, is a shaft 101 having two drums 102 to which are secured the ends of the cables 61 and 62. The drums 102 are fast to the shaft 101.

A flexible coupling 103 connects the shaft 101 to a shaft 109 which extends into a "box" 104 representing a well known standard gear reduction mechanism. This gear reduction may be one of the standard 48 to 1 reductions. The shaft 103 is connected to this gear reducing mechanism, which also has connected thereto a shaft 105, in turn connected by a flexible coupling 106 to a shaft 107 driven by a motor 108.

When the door 20 is closed as shown in Fig. 11, and it is to be opened the operator merely pushes a standard electrical switch (not shown) to start the motor 108, whereupon through the means above described the shaft 101 is rotated with the drums 102 and the cables 61 and 62 are wound upon said cables thus opening the door 20. When the door reaches the proper place a limit switch represented by a "box" 110 cuts the current to the motor and it stops with the door 20 fully opened.

To close the door 20 the operator presses another standard switch to reverse the action of the motor, whereupon the door 20 will start downwardly due to the fact that there are no counterweights 77 or 87 used with the motor operator.

The door 20 cannot fall because the gear reducing mechanism 104 now acts as a brake and lets the door come down easily until it is fully closed.

In order to make a tight fitting job of the door 20, I have provided weather strips on each side along the lines of the door edges and the jams 21 and 22. However since this type of door swings outwardly, the weather strips are divided as shown in Fig. 9. One strip 111 is secured to the inside of the door and overlaps each side thereof. This strip is bevelled as at 112, the lowermost point of the bevel being at the horizontal center line 91, since from this point upwardly the strip does not pass beyond the lines of the jams 21 and 22. The lower part of the strip 113 is bevelled to fit the bevel 112. This strip 113 is secured to the inside of each of the jams 21 and 22 and of course is stationary.

Since a full description of the operation of my novel door construction has been given along with the detailed description, it is not thought necessary to repeat that operation at this time.

While the form of device herein shown and described is admirably adapted to fulfil the objects primarily stated, it is to be understood that my invention is not limited to the form shown, as other forms, all coming within the scope of the claim which follows, may be used without departing from the spirit of my invention.

What is claimed is:

A movable panel supporting a bracket therefor rigidly secured to the panel; an upright member; a bearing integral with the bracket and pivoted on said member; a cable guiding and supporting device carried by the supporting bracket adjacent the top thereof; a cable secured to the bracket at a point substantially on a horizontal center line passing through the bearing; said cable running from said point up and over said device whereupon all of the thrust accompanying one movement of the panel is against said device until the point of attachment of the cable to the bracket nears the vertical center line passing through said bearing, at which time the device leaves the cable and the thrust is transferred to said point of attachment until the panel reaches the end of its movement at which time the point of attachment is past said vertical center line, and as the panel is returned to its normal position the guiding device again contacts the cable after the point of attachment has moved in the opposite direction past the vertical center line to transfer the thrust from said point of attachment back to the guiding and supporting device until the panel reaches its normal position.

WILLIAM E. HERGENRATHER.
